UNITED STATES PATENT OFFICE

161,845

GAME TABLE OR SIMILAR ARTICLE

Lester G. Larson, Chicago, Ill.

Application April 4, 1949, Serial No. 1,796

Term of patent 14 years

(Cl. D34—5)

To all whom it may concern:

Be it known that I, Lester G. Larson, a citizen of the United States, residing in the city of Chicago, in the county of Cook and State of Illinois, have invented a new, original, and ornamental Design for a Game Table or Similar Article, of which the following is a specification, reference being had to the accompanying drawings, forming a part thereof.

Fig. 1 is a top plan view of the game table or similar article, showing my new design;

Fig. 2 is a side elevational view thereof; and

Fig. 3 is a perspective view thereof.

I claim:

The ornamental design for a game table or similar article, substantially as shown.

LESTER G. LARSON.
